UNITED STATES PATENT OFFICE.

EDWARD J. POWERS, OF CHICAGO, ILLINOIS.

AUTOMATIC WATER-HEATER.

1,116,915.

Specification of Letters Patent.

Patented Nov. 10, 1914.

Application filed October 28, 1913. Serial No. 796,964.

To all whom it may concern:

Be it known that I, EDWARD J. Powers, a citizen of the United States of America, and a resident of Chicago, in the county of Cook, State of Illinois, have invented certain new and useful Improvements in Automatic Water-Heaters, of which the following is a specification.

This invention relates to that type of automatic water heaters used for heating water for household purposes, and has for its object to provide a simple and efficient structural formation and combination of parts of the motor mechanism which is operated by the flow of the water through a heating apparatus and is adapted to automatically control the supply of gaseous fuel to the burner of said apparatus, and with which exposed moving parts and packing glands therefor are avoided, and the consequent malicious tampering with, damage to and leakage from said parts is prevented and a sensitively operating mechanism provided, all as will hereinafter more fully appear.

In the accompanying drawings:—Figure 1, is a sectional elevation, illustrating the general arrangement of parts in the present invention. Fig. 2, is a detail plan view of the primary regulator with its arrangement of pipes and ducts.

Similar reference numerals indicate like parts in both views.

Referring to the drawings, 1 represents a tubular hot water heater or generator of any usual and suitable construction, and which is provided with the usual water inlet connection or pipe 2; water outlet connection or pipe 3, and gas burner 4 having a gas supply branch or pipe 5, as shown.

6, is a chamber or casing arranged in communication or circuit with the outlet pipe or connection 3, and its pipe continuation 7, so that the heated water on its way from the heater will pass through said chamber and influence the hereinafter described thermostatic device which controls the supply of fuel gas to the burner 4.

8 is the casing of the primary regulator of the present invention, and which comprises a detail arrangement of parts as follows:—9 is a central motor chamber formed in said casing, and in said motor chamber are disposed upper and lower pistons or diaphragms 10 and 11, the upper one of which is of a greater area than the lower

one, and is preferably provided with the usual reinforcing disk or button 12 on its upper side, as shown. While it is preferable to form the diaphragms 10 and 11 of composite sheets of rawhide and rubber, it is within the province of this part of the present invention to use any other ordinary form of diaphragm or piston when so desired. The lesser area of the lowermost diaphragm 11, above referred to, is attained in the construction shown in Fig. 1, by the formation beneath the same of a central recess or chamber 9' in the casing 8, aforesaid. With such construction, in a normal upward movement of the diaphragms and their accessories, the lower diaphragm 11 will move upwardly above the aforesaid recess 9' and will consequently expose a much smaller area to active pressure than the upper diaphragm 10, the whole area of which is exposed to such active pressure.

13 is an upper valve chamber formed in the aforesaid casing 8, and having an intermediate valve seat for the gravity or ball valve 14. Said valve seat divides the chamber into an upper sub-chamber which is in communication with the outlet pipe continuation 7 above described, and with the motor chamber 9 at a point between the aforesaid diaphragms 10 and 11 by a branch passage 15, as shown, and into a lower sub-chamber that has communication with the outlet branch pipe 16, in which is the outlet faucet or faucets of the structure. In the described construction the passage between the aforesaid lower sub-chamber and the chamber above the upper diaphragm 10, is made larger than the diameter of that portion of the hereinafter described valve stem which is disposed in said passage, and with a view to allow for a free passage of water between said chambers.

17 is a lower valve chamber formed in the aforesaid casing 8, and having a valve seat 18, an inlet fuel gas pipe 19 and an outlet fuel gas pipe 20, as shown.

21 is the valve stem above referred to, and which is operatively connected to the diaphragms 10 and 11. The upper end of said valve stem is disposed in operative relation to the ball valve 14, aforesaid, and is adapted to unseat said valve in an upward movement of said valve stem, under the influence of the upper diaphragm 10, in manner hereinafter described in detail. The lower end of said valve stem 21, is provided with a

valve head 22, controlling the valve seat 18, the opening of which is a continuation of the outlet gas passage 20, above described.

- 5 With the above described arrangement of parts, as an outlet faucet in the outlet branch pipe 16, is opened, the water above the upper diaphragm 10, escapes, permitting the pressure in the motor chamber 9, to 70 raise said diaphragm 10, and force the valve 14 from its seat, thus affording a direct outflow of hot water from the branch pipe 7 and through the aforesaid outlet branch pipe 16, as long as the aforesaid faucet remains open. Simultaneously with the above 75 described lifting of the ball valve 14, by the valve stem 21, the valve head 22 carried on the lower end of said valve stem is lifted away from the valve seat 18 to permit the passage of fuel gas to the burner 4 of the heater. In the described construction the normal tendency of the aforesaid valve head 22, is to a closure engagement with the aforesaid seat 18, so that 80 when the flow of hot water through the outlet branch pipe 16, is shut off, the influence of the lower diaphragm 11, combined with gravity is adapted to automatically attain such closure.
- 20 23 is an inner casing disposed within the interior of the casing 6, before described, and containing a filling of heavy mineral oil, or like expansible fluid. Said casing being wholly immersed in hot water passing through the outer casing 6, is adapted 85 to attain approximately the same temperature as that of the passing water, and the heat transference may be expedited by the formation of said inner casing 23, with 90 passages, fins or ribs, as usual in the heat transference art. The transference of heat above mentioned, is in turn transmitted to or from the heavy mineral oil filling in the casing 23, and the consequent expansion 95 or contraction of said filling is in turn utilized to regulate the flow of fuel gas to the burner 4 of the heater, by the following arrangement of parts:—24 is a piston chamber forming an extension of the casing 23, and having a piston 25, one end of 100 which is exposed to the oil filling above described, while the other end is connected to the carrying lever of a regulating valve mechanism now to be described.
- 25 26 is a valve casing, preferably connected to the aforesaid piston chamber 24, and having communication with the fuel gas supply pipes 5 and 20, heretofore described, and in the present construction the pipe 5 105 ends in a valve seat 27 disposed in the interior of the valve casing 26, and controlled by the movable valve mechanism as follows: 28 is a lever pivoted within the valve casing 26, and operatively connected to the 110 piston 25, above described.

29 is a valve head carried on the free end of the lever 28 and disposed in operative relation to the valve seat 27, aforesaid. In the preferred construction said valve head is provided with a headed and elongated stem 30, having limited independent movement in a receiving orifice formed therefor in the lever 28. With the described construction limited independent movement of the lever 28, in its valve closing and opening movements is permitted, so that in one case the valve 29 will be carried into adjacent relation to the seat 27, and close rapidly on said seat under the influence of the flow of gas, and in the other case will be drawn away from the valve seat and attain a sudden and full opening effect by gravity.

With the above described valve regulating mechanism, as the water passing away from the heater 1, reaches a higher temperature than required, the consequent expansion of the heavy mineral oil in the casing 23, is adapted through the intermediate valve adjusting mechanism above described, to shut off the fuel gas supply to the burner 4, until the temperature of the passing hot water drops to a normal and predetermined temperature, when the supply of gas will be restored automatically by the removal of the valve head 29 from the seat 27. Otherwise the normal position of the valve head 29 is the opened condition illustrated in Fig. 1, in order to permit the proper performance of the primary regulator first described.

With the present arrangement of the automatic regulating means in the outlet pipe from the water heater, an uninterrupted and full supply of water to such heater is insured under all conditions. And what is of still greater consequence, such arrangement effects an entire elimination of retardation due to friction of the volume of water in the ramifications of the water heater aforesaid, and provides instead an almost entire absence of pressure at one side of the automatic regulating mechanism, and the full pressure of the water main or supply at the other side of said mechanism. In consequence a rapid and sensitive control of the fuel gas supply is attained.

Having thus fully described my said invention what I claim as new and desire to secure by Letters Patent, is:—

1. A motor for hot water heating system, comprising a single motor casing having a central motor chamber, upper and lower valve chambers and a by-pass connecting the upper valve chamber with the central motor chamber, a gravity valve arranged in the upper valve chamber, an inlet branch connecting with said valve chamber above said valve, an outlet branch connected to said valve chamber below said valve, a pis- 120

ton in the central motor chamber aforesaid, a piston stem carried by said piston and having operative engagement with the gravity valve aforesaid, an inlet branch connected to the lower valve chamber, an outlet branch connected to the lower valve chamber and provided with a valve seat and a valve head associated with said seat and having operative engagement with the piston stem aforesaid, substantially as set forth.

2. A motor for hot water heating systems, comprising a single motor casing having a central motor chamber, upper and lower valve chambers and a by-pass connecting the upper valve chamber with the central motor chamber, a gravity valve arranged in the upper valve chamber, an inlet branch connecting with said valve chamber above said valve, an outlet branch connected to said valve chamber below said valve, upper and lower pistons of differential areas in the central motor chamber aforesaid, a piston stem carried by said piston and having operative engagement with the gravity valve aforesaid, an inlet branch connected to the lower valve chamber, an outlet branch connected to the lower chamber and provided with a valve seat, and a valve head associated with said seat and

having operative connection with the piston stem aforesaid, substantially as set forth.

3. A motor for hot water heating systems, comprising a single motor casing having a central motor chamber, upper and lower valve chambers and a by-pass connecting the upper valve chamber with the central motor chamber, a gravity valve arranged in the upper valve chamber, an inlet branch connecting with said valve chamber above said valve, an outlet branch connected to said valve chamber below said valve, upper and lower diaphragm pistons in the central motor chamber aforesaid, a piston stem carried by said pistons and having operative engagement with the gravity valve aforesaid, an inlet branch connected to the lower valve chamber, an outlet branch connected to the lower chamber and provided with a valve seat and a valve head associated with said valve seat and having operative connection with the piston stem aforesaid, substantially as set forth.

Signed at Chicago, Illinois, this 21st day of October, 1913.

EDWARD J. POWERS.
